UNITED STATES PATENT OFFICE.

CHARLES E. DOUGLAS, OF NASHUA, NEW HAMPSHIRE.

SHEET-METAL SNOW GUARD.

Application filed January 6, 1927. Serial No. 159,425.

This invention relates to snow guards which are applied to roofs, particularly of the sloping type, and particularly those surfaced by courses of slate, tile, wooden or asbestos shingles. Such snow guards are for the purpose of holding back and breaking up snow and ice which forms on such roofs and prevent it from sliding in heavy masses off the eaves.

10 Such snow guards should be attractive in appearance and of strength at certain points such as the horizontal platform and its supporting web while the part which generally extends up under a shingle should be as thin as possible.

The snow guard is preferably made of some material such as copper to resist rust, and be of attractive appearance but which has not tremendous natural strength.

20 It is desirable that the snow guard should be made of sheet material as far as possible for lightness and cheapness.

The purpose of this invention is to form a snow guard of sheet metal which is economized as far as possible without the sacrifice of strength or appearance.

25 In the drawings, Fig. 1 is an elevation of the rectangular sheet metal blank from which the device is formed.

30 Fig. 2 is an elevation of the blank as it is first cut.

Figs. 3, 4, 5, 6, 7 and 8 show the successive vendings to make the completed article.

Fig. 9 is a side elevation of the finished 35 snow guard.

Fig. 10 is a perspective from the front of the finished snow guard.

Fig. 11 shows a blank cut in a slightly different way.

40 Fig. 12 shows the first bending of the blank shown in Fig. 11.

Fig. 13 shows the complete snow guard formed from the blank shown in Fig. 11.

Fig. 14 is a side elevation of Fig. 13 from 45 the left.

In the drawings, A represents a rectangular sheet of metal, preferably copper or galvanized iron, having the top 14 bottom 13 and sides 10 and 11.

50 In Fig. 2 is shown the medial vertical cut 20, the two sides of which, 23 and 24, are spaced apart the cut running vertically downward dividing blank A into the right and left sections C and B.

55 At the bottom of cut 20 extending a short distance to the right is a cross cut, the bot-

tom line of which is indicated at 29 and the top line shown as extending diagonally up to the left shown at 25.

In Fig. 3, I show the lower left corner 60 of left section C bent up on a diagonal line 28 to form a double thick triangular supporting web F the top edge being indicated at 129 and the side by 27.

The left section C together with web F 65 are now bent back 90° on a vertical line 58 extending down medially from the bottom edge 29 of the cross cut 26.

The left section C and web F are then 70 bent forward 180° on the line 57 which extends vertically downward from the right end of base 29 of cross cut 26 parallel with the line 57, the various bendings being so positioned that as shown in Fig. 5, the left section C now extends directly forward at 75 right angles to the attaching section B and approximately in the middle thereof.

Section C is now bent to the right at 44 forming a plate 40 thence to the left at 42, the plate 40 being bent down to the position 80 shown at 41 in Fig. 7 and this part 41 with the part 46 lying underneath it is bent over on the line 43 so that it extends to the right beyond the part 47 of section C, all the bendings being so positioned as to form a platform 85 which is double thick at the right and triple thick at the left.

The supporting web F is double thick while the attaching part B from which 90 preferably is cut a hook H in a well known manner, is single thick.

As shown in Figs. 11, 12 and 13 I may use a blank and cut the vertical line 60 from a point about two-thirds to the left thence at 95 the bottom extend the cross cut 61 half way forming a platform section K and attaching section L and the bottom section M.

The lower left corner is bent up on the diagonal line 62 forming a supporting web P having a top edge 63 and back edge 64.

The parts K and P are now bent forward 100 90° and the top part of the section K is bent to the left on the line 65 forming a plate 66, thence again to the right on the line 67 forming the top plate 68, thence again down to the left on the line 69 forming a bottom plate 70.

105 It will be seen that a platform N is thus formed which is double thick while the web P is also double thick.

110 It will be observed that in this last construction there is a gap indicated by 159

which practically represents the length of the cross cut 61. With some type of shingles it is desirable that this gap should be considerable to include the thickness of the end of a shingle.

On the other hand, as shown at 59 in Fig. 9, the gap may be very slight or nothing at all. If the lines 57 and 58 are caused to coincide the gap 59 is entirely closed.

19 I claim:

1. A snow guard formed of a single sheet of metal, cut medially and vertically downward forming right and left sections connected at the bottom, a cross cut extending 15 at the bottom a short distance to the right, the lower left of the left section being bent on a diagonal line to form a double thick triangular supporting web, the web and left section being bent back ninety degrees on a 20 vertical line extending down medially of

the cross cut, and thence forward on a vertical line from the right end of the cross cut to extend ninety degrees forward, and the left section being then bent right and left to form a platform resting on the top of the 25 web.

2. A snow guard formed of a single sheet of metal, cut medially and vertically downward forming right and left sections connected at the bottom, a cross cut extending at 30 the bottom a short distance to the right, the lower left of the left section being bent on a diagonal line to form a double thick triangular supporting web, the web and left section being bent on a vertical line from the right end of the cross cut to extend ninety degrees forward, and the left section being then bent right and left to form a platform 35 resting on the top of the web.

CHARLES E. DOUGLAS.
